US0D1037289S

(12) **United States Design Patent** (10) Patent No.: **US D1,037,289 S**
(45) Date of Patent: ** Jul. 30, 2024

(54) **DISPLAY SCREEN OR PORTION THEREOF WITH GRAPHICAL USER INTERFACE**

(71) Applicant: **RITE-HITE HOLDING CORPORATION**, Milwaukee, WI (US)

(72) Inventors: **James C. Boerger**, Franksville, WI (US); **Richard Mews**, Bonduel, WI (US); **Kenneth C. Bowman**, Cedarburg, WI (US)

(73) Assignee: **RITE-HITE HOLDING CORPORATION**, Milwaukee, WI (US)

(**) Term: **15 Years**

(21) Appl. No.: **29/858,413**

(22) Filed: **Oct. 31, 2022**

Related U.S. Application Data

(60) Division of application No. 35/001,714, filed on Jul. 22, 2019 (U.S. filing date under 35 U.S.C. 384), and having an international filing date of Jul. 22, 2019, now Pat. No. Des. 968,451, which is a continuation of (Continued)

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer broken line rectangle showing a display screen or portion thereof, as well as all remaining interior broken lines showing portions of the graphical user interface, form no part of the claimed design. The stacked dot colon feature forms part of the claimed design as shown.

1 Claim, 1 Drawing Sheet
